(57) **CLAIM**

The ornamental design for an outdoor component enclosure, as shown and described.

DESCRIPTION

FIG. 1 is a front side perspective view of an outdoor component enclosure showing the design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof;

FIG. 7 is a left side elevational view thereof;

FIG. 8 is a front elevational view thereof; the broken lines indicate an environmental structure that forms no part of the claimed design;

FIG. 9 is a front elevational view thereof; the broken lines are for illustrative purposes only and form no part of the claimed design;

FIG. 10 is a rear elevational view thereof; the broken lines indicate an environmental structure that forms no part of the claimed design; and,

FIG. 11 is a bottom plan view thereof; the broken lines indicate an environmental structure that forms no part of the claimed design.
